UNITED STATES PATENT OFFICE.

WILLIAM P. SEMON, OF BROOKLYN, NEW YORK.

INDICATOR.

1,315,425.

Specification of Letters Patent.

Patented Sept. 9, 1919.

Application filed April 30, 1918. Serial No. 231,744.

To all whom it may concern:

Be it known that I, WILLIAM P. SEMON, a citizen of the United States, and residing at Brooklyn, in the county of Kings and State of New York, have invented a new and Improved Indicator, of which the following specification is a full disclosure.

This invention relates to display devices and it has for its object the creation of an automatic device for intermittently displaying a succession of legends, announcements, advertisements, or the like. Heretofore, many different devices of this general nature have been proposed but not without involving considerable mechanical complexity. This invention seeks to effect such improvements in the direction of simplification as to render devices of this nature more available in a commercial sense and more satisfactory in point of operation.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a front elevation of a display device constructed in accordance with this invention. Fig. 2 is a vertical section taken along line 2-2 of Fig. 1. Fig. 3 shows a detail of the escapement mechanism of the reels and Fig. 4 shows an axial section of the same.

Referring to the drawings, the legends to be successively displayed are printed on a long flexible band 7 of suitable material. The ends of this band are wound up on reels 11 and 8, respectively, which are arranged a sufficient distance apart to provide the necessary display space on the band and these reels are suitably journaled in a casing hav-

ing a window for exposing the successive legends on the band.

An actuating instrumentality is provided for the purpose of intermittently winding the band alternately on the reel 11 and the reel 8. That is to say, this instrumentality operates to intermittently wind the band on the reel 11 so as to expose the successive legends. Preferably also, the instrumentality permits of a similar operation in a reverse direction to successively expose the legends in reverse order by winding the band intermittently on the other reel 8.

The operating instrumentality is so constructed that the intervals between its successive operations are controlled by hand, according to the desires of the user. To that end, the operating instrumentality is so constructed that, by successively pressing a button, the band will be automatically moved through a sufficient distance to displace the one legend and properly expose the succeeding legend. An electric motor 1 is mounted in the casing or frame and is provided with suitable wiring whereby, upon actuating a suitable circuit-closer in the nature of a button, the motor will be energized and caused to rotate continuously unless the contact is closed. The construction is such that, although the motor may thus operate continuously, it will merely have the effect of rotating the band 7 through a distance corresponding to the spacing between the legends.

This is accomplished by an intervening driving mechanism so constructed as to be operative during the first few revolutions of the motor but to become inoperative thereafter and to automatically resume its operative condition as soon as the motor is de-energized so that it will again function when the motor is once more energized. This intervening mechanism comprises an endless chain 3 riding around sprocket wheels, the one being in the nature of a mounting or bearing and the other, indicated by 4, being secured to a shaft which is connected by ratchet mechanism with the adjacent reel so that when the sprocket wheel 4 is turned by motor power in the one direction it will (through the ratchet device) turn the reel 8 in the same direction; this direction corresponding to the winding-up direction of the belt on the reel 8. When, however, the sprocket wheel 4 is turned in its reverse direction, it will be without effect on the reel 110

8 and this reverse movement is utilized for restoring the actuating instrumentality to its operative condition. The endless chain 3 is provided with a number of teeth 13 and 5 the motor 1 is provided with a toothed wheel 2, so mounted as to engage the projections or teeth 13 on the endless belt (see Fig. 2), so that when the motor rotates it will cause the endless chain to travel and (through the 10 ratchet device) turn the reel 8. As soon as the reel has been turned through a distance sufficient to expose the next legend on the belt 7, the toothed wheel 2 will reach the end of the teeth 13 on the endless chain, *i. e.*, it 15 will reach the blank space 9 and consequently be unable to further rotate or advance the endless chain. The advance of the belt 7 now ceases and the next legend has been exposed. This condition prevails so long as the circuit 20 is kept closed and the motor 1 is kept in operation but as soon as the circuit is opened and the motor 1 becomes deenergized, the weight 10, which is attached to the endless chain, is unable to effect a reverse movement in the 25 endless chain and this is done by rotating the motor idly in a backward direction until the weight 10 reaches its lowermost level. One cycle in the machine has thus been completed. The next cycle will take place in a corresponding manner until all of the legends on the belt 7 have been reeled up on the reel 8.

A similar operating instrumentality, consisting of another motor, another endless chain 13, another idle sprocket 9, another 35 weight 14, and an analogous ratchet device 12, is arranged in operative relation with the other reel 11 so that the belt 7 may be intermittently returned to the reel 11 by actuating a second circuit closer.

40 The construction of the ratchet mechanisms is shown by Figs. 3 and 4. A pawl 12 is pivoted to the operating shaft and its relation is such that when the weight 10 is at its lowermost region, the pawl will be disengaged by gravity and will assume the position shown by Fig. 3. In other words, it is now entirely disconnected and, therefore, will not interfere with the reverse reeling action of the other actuating instrumentality. When, however, the shaft on which the pawl is mounted is turned, the pawl will immediately by gravity, engage the internal 45 ratchet of the reel 11 and the operation will take place as aforesaid. At the end of each 50 cycle, the pawl will assume its inoperative position.

It will thus be seen that this device, while

exceedingly simple in construction, is nevertheless capable of operating effectively and does not involve any mechanical complexity. It is of utility as a display board for vaudeville theaters or wherever it may be desirable to advertise or announce performances or the like.

Without further analysis, the foregoing will 60 so fully reveal the gist of this invention that others can, by applying current knowledge, readily adapt it for various applications without omitting certain features that, from the standpoint of the prior art, fairly constitute essential characteristics of the generic or specific aspects of this invention, and therefore such adaptations should be and are intended to be comprehended within the meaning and range of equivalency of the 65 following claims.

Having thus revealed this invention, I claim as new and desire to secure the following combinations of steps and elements, or equivalents thereto, by Letters Patent of the 70 United States:

1. An advertising apparatus comprising two reels; a belt adapted to be wound intermittently from the one reel onto the other, and conversely; actuating mechanism normally disconnected from said two reels; manually controlled means for automatically connecting said mechanism successively with one of said reels and for automatically disconnecting it therefrom after it has advanced 85 said reel through a predetermined number of revolutions; and means for automatically restoring said mechanism to its initial condition.

2. A display apparatus combining a display belt; a member for operating said belt; a ratchet mechanism for intermittently operating said member successively in one direction and ineffective to operate it in the other; and manually controlled means for 90 repeatedly moving said ratchet mechanism in its operative direction for a predetermined number of revolutions, said ratchet mechanism being constructed to automatically become disconnected when restored to 100 its initial condition.

In testimony whereof, I have signed this specification in the presence of two subscribing witnesses.

WILLIAM P. SEMON.
